(57) **CLAIM**

The ornamental design for the pain management apparatus, as shown and described.

DESCRIPTION

FIG. 1 is a perspective view of the present invention engaged with a user; and

FIG. 2 is a front view of the present invention engaged with a user; and

FIG. 3 is a rear view of the present invention engaged with a user; and

FIG. 4 is a right side view of the present invention engaged with a user; and,

FIG. 5 is a left side view of the present invention engaged with a user.

The broken line showing immediately adjacent to shaded areas depicting the human form and a pocket tool member is included for the purpose of illustrating environment and forms no part of the claimed design.
